PIPE-CLEANING MACHINE

Warren A. Kraner, San Francisco, Calif., assignor to General Paint Corporation, San Francisco, Calif., a corporation of Nevada

Application June 2, 1947, Serial No. 751,816

10 Claims. (Cl. 51-9)

1

This invention relates generally to machines used for the cleaning of metal pipe. Such machines find useful application for the conditioning or cleaning of both new and old pipe, where it is desired to remove mill scale, rust or portions of previously applied coating material.

Machines of the above character have been available in the past but have been subject to various disadvantages. Generally such machines are relatively complicated, expensive, and somewhat difficult for use by average operators. In addition the mechanisms used for cleaning the surface of the pipe have frequently been either ineffective for proper cleaning or too severe. Grit blasting has been found reasonably effective for such cleaning operations but no pipe cleaning machine has been produced which satisfactorily incorporates grit blasting devices.

It is an object of the invention to provide a successful pipe cleaning machine which utilizes grit blasting devices and which is capable of continuous operation over a substantial length of pipe.

A further object of the invention is to provide a pipe cleaning machine having wide adaptability and flexibility, and which can be used for a wide variety of services.

Additional objects of the invention will appear from the following description in which the preferred embodiment has been set forth in detail in conjunction with the accompanying drawing.

Referring to the drawing:

Figure 1 is a side elevational view in section illustrating a machine incorporating the present invention.

Figure 2 is a cross-sectional view taken along the line 2-2 of Figure 1.

Figure 3 is a detail illustrating a suitable arrangement of supporting rollers upon the pipe to be cleaned.

Figure 4 is an end view looking toward the left end of Figure 1.

Figure 5 is an end view of the machine looking toward the right hand end of Figure 1.

Figure 6 is a side elevational view in section illustrating another embodiment of the invention.

Figure 7 is a cross-sectional detail of the embodiment illustrated in Figure 6.

Figure 8 is a cross-sectional detail showing the operating head of the blasting units.

Figure 9 is an enlarged cross-sectional view of the blasting unit.

The machine illustrated in Figures 1 to 5 of the drawing consists generally of a circularly contoured housing 10 formed in this instance of two sections 10a, 10b. These sections have a hinged connection 11 whereby they can be swung apart to permit removal or application with respect to pipe 12. Each section of the housing includes

2

the circularly contoured peripheral wall 15, and the end walls 13, 14. Circular openings 16, 17 in the end walls accommodate the pipe 12, and the spaces about the pipe are closed by the annular curtains 18, 19 which can be formed of suitable flexible material, such as resilient sheet rubber.

Suitable means are provided for tracking the housing upon the pipe whereby the housing can be rotated about the pipe and simultaneously advanced longitudinally. For this purpose two sets of rollers are provided, one set being carried by wall 13, and the other by wall 14. Rollers 21 constituting the first set are suitably journaled to the brackets 22, which in turn are bolted to the mounting pads 23. These pads in turn are bolted to the brackets 24 which are adjustably secured to the adjacent end wall 13 by bolts or screws 26. A pair of driving motors 27a, 27b are provided, and these motors are suitably carried by mounting brackets 28, attached to the adjacent end walls 13. Suitable driving belts or chains 29a, 29b connect the motors 27a, 27b to adjacent pairs of rollers 21 as shown in Figure 4. Preferably the motors 27a, 27b are provided with a suitable reduction gearing to provide a proper speed of drive. In a typical instance the drive can be such that the rate of rotation of the housing 10 can be of the order of 20 R. P. M.

The other set of rollers carried by the end walls 14 are similar to the rollers previously described. Thus rollers 31 are carried by pads 32 which in turn are attached to the supporting brackets 33. All of the rollers can be faced with resilient rubber to enable frictional contact with the pipe.

In practice the rollers described are set at a small angle with respect to the longitudinal axis of the pipe 12 in order to provide a proper rate of advance of the machine longitudinally of the pipe as it is revolved. Such angularity has been illustrated in Figure 3 and in a typical instance the angle of the axis of the rollers with respect to the longitudinal axis of the pipe can be of the order of 5°.

Each housing section carries a grit blasting unit 36a, 36b. The units shown in Figures 1 to 5 are of a type available on the market utilizing a spinning wheel into which grits can be fed and which stores and discharges the grits in the form of a fan-shaped spray or blast. One unit of this type is known by the trade as "The Pangborn Vaneless Rotoblast Wheel" and is sold by Pangborn Corporation. Such a unit includes the wheel 37 which is shown applied directly to the shaft of the electric motor 38. The interior of the wheel is hollow and the rim 39 is provided with an inclined or conical shaped inner face 41. The front face of the wheel is provided with an outer rim 42 or ledge over which grits pass

in effecting discharge of the same. A rotary disc-like plow 43 is associated with the wheel and can be adjusted to a position with its rim touching the layer of material upon the surface 41. A feed tube 44 leads from the hopper 46 through the interior of the wheel, through the annular baffling 47. A second feed tube 44a leads from the interior of the wheel to the hopper 46a, located inwardly from the outer periphery of the housing.

The mounting for the motor 38 is preferably constructed in such a manner that the motor is protected from the interior of the housing. Thus the motor is attached to plate 49, which in conjunction with the walls 51 interposed between the motor and the wheel 37, serves to protect the motor from the interior of the housing. In the operation of such a centrifugal blasting machine grits are fed down through tubes 44 and 44a from hoppers 46 and 46a and a substantial quantity of grits from a bed upon the inner inclined wheel wall 41. Grits are continuously removed from this bed by the plow wheel 43, thus causing a fan shaped discharge blast 52. The arrangement is such that this blast is directed upon the exterior of the pipe at an angle selected to secure optimum cleaning.

In the operation of my machine it is necessary to provide means for continually removing smaller dust particles comprising rust or like corrosion, particles of previously applied coating material, or like fragments which are removed from the pipe and intermingle with the grits. For this purpose centrifugal blowers 53 are shown mounted upon the end walls 14, and can be driven by suitable motors 54. The intake openings 56 to the blowers 53 are provided with suitable screening means (not shown) to avoid entrance of grits. Blowers 53 operate continuously to remove the smaller fragments from the interior of the housing as the machine operates.

The necessary electrical connections to the various motors of the machine lead to a suitable slip ring assembly (not shown) and thus to a source of current supply.

Operation of the machine described above is as follows: The housing is applied to a pipe to be cleaned and an ample charge of grits placed in the housing. Ordinary steel grits can be used such as are commonly employed for impact cleaning operations. All of the motors are now placed in operation. As the housing revolves about the pipe it is passed longitudinally along the pipe at a predetermined rate. During each revolution of the housing grits are received in the hoppers 46 and 46a of each blasting unit, and the grits provided in this manner serve to replenish the charge of grits in each wheel. Thus assuming rotation in the direction indicated by arrows in Figure 2, the supply of grits 57 accumulated in the lower part of the housing is filling the adjacent hopper 46a, while the hopper 46 of the uppermost blasting unit is discharging its supply of grits. The lowermost hopper 46a is receiving some of the grits falling from the pipe and is supplying such grits to the lower blasting unit. The blast 52 from each of the two units is fan-shaped as previously mentioned and the speed of advance should be such that a given surface area of the pipe is subjected to the blast a number of times. Foreign material thus removed from the surface of the pipe is continuously removed from the housing by way of blowers 53. Each wheel 39 is capable of storing a considerable charge of grits and therefore the units provide a continuous blast irrespective of

possible interruptions in the supply of grits from the hoppers.

In general my machine is capable of effective cleaning action to the extent necessary to remove mill scale from new pipe, or rust or like corrosion or fragments of coating previously applied. Undue removal of metal or like injury to the pipe can be avoided. No undue skill is required in the operation of the machine and when once placed in operation it can operate continuously over an extended length of pipe. Ordinary couplings such as are used on pipe sections can be passed without difficulty, and thus the device is well adapted for field conditions where it is frequently desirable to clean raised lengths of pipe without disconnecting the same.

The embodiment of the invention illustrated in Figures 6 to 9 inclusive employs a different type of blasting unit. Each of the mountings 61 (Figure 7) for the motor 38 of the associated blasting unit has an opening 62 of sufficient size to pass the blasting head. The motor itself is secured to an L-shaped mounting bracket 63, which when attached by bolts to the mounting 61, completely covers the opening 62. Attached to the mounting bracket 63 there is a guard 64 which is flared toward an inwardly faced open side 66 (Figure 6). A rotor 67 is mounted upon the shaft of the motor 38, and consists of inner and outer annular assemblies 68 and 70 which are fixed to the rotor shaft. The inner assembly 68 includes the spaced discs 68a, 68b and the circumferentially spaced vanes 69. The outer assembly includes the spaced discs 70a, 70b and the spaced vanes 71. Interposed between the two assemblies 68 and 70 there is a relatively stationary cylindrical shaped discharge control member 72. This member has an opening 73 in one side of the same through which grits may pass.

The inner assembly 68 of the rotor also carries a series of circumferentially spaced arcuate bars or plates 74 which are in close proximity with the inner periphery of member 72. Slots 75 are provided between the plates 74, and it will be noted that these slots are formed between opposed edges of the plates which are of different radial thickness, and that the slots have decided outward divergence to avoid clogging or blocking.

In operation of the machine, grits are recurrently supplied to the space 79 within the rotor. Thus a pair of spouts 81 and 82 are provided which discharge grits into the space 79, and which in turn lead from the hoppers 83 and 84. Both the spouts and the hoppers are carried by plate 86 which is demountably attached to a flange carried by member 72. This flange in turn is removably attached to the housing wall 87.

Operation of the embodiment illustrated in Figures 6 to 9 inclusive is as follows: During rotation of the housing 10 the hoppers 83 and 84 are recurrently filled with grits, and such grits are recurrently supplied to the inner rotor space 79. The grits are thrown outwardly and given considerable rotary movement by the action of the vanes 69. Likewise these vanes serve to effect circumferential distribution of the grits. As the grits strike the plates 74 there is a temporary storage or retention while at the same time grits are fed outwardly through the slots 75, and through the opening 73, to be impelled by the vanes 71 to discharge the same upon the pipe as illustrated in Figures 6 and 7.

During certain intervals of the rotation of the housing 10, no grits may be supplied to the space

79 through the spouts 81 and 82. For such intervals there is sufficient storage of grits upon the inner faces of the plates 14 to provide for continued feeding of grits to the vanes 11, so that the blasting action continues without interruption.

This application is a continuation-in-part of my co-pending application Serial No. 664,646, filed April 24, 1946 and now abandoned.

I claim:

1. In a pipe cleaning machine, a housing adapted to surround a pipe to be cleaned, a grit blasting unit carried by said housing and adapted to discharge grits upon the sides of the pipe, means for rotating the housing about the pipe and for simultaneously advancing the same longitudinally about the pipe, and means for supplying grits to said unit.

2. In a pipe cleaning machine, a housing adapted to generally surround the pipe to be cleaned, a grit blasting unit carried within the housing and adapted to discharge grits upon the surface of the pipe, the housing being adapted to contain a quantity of grits for supplying grits to said unit, and means for rotating said housing about the pipe and for simultaneously advancing the same longitudinally of the pipe.

3. In a pipe cleaning machine, a housing adapted to surround a pipe to be cleaned, said housing serving to contain a quantity of grits, at least one grit blasting unit carried by said housing, said unit including a rotary blasting wheel for centrifugal discharge of grits upon the pipe and hopper means for supplying grits to the wheel, said hopper means being open to the interior of the housing, and means for rotating the housing about the pipe and for simultaneously advancing the same longitudinally of the pipe.

4. In a pipe cleaning machine, an annular hollow housing formed in sections and adapted to be assembled about a pipe to be cleaned, means for rotating the housing about the pipe and for advancing the same longitudinally of the pipe, grit blasting units carried by said sections, each of said units comprising a rotary blasting wheel for centrifugal discharge of grits upon the pipe together with hopper means open to the interior of the housing and serving to supply grits to the wheel, said housing being adapted to contain a supply of grits whereby upon rotation of said housing grits are supplied recurrently to the hoppers of said blasting units.

5. A pipe cleaning machine as in claim 4 in which the hopper means comprises two hoppers for each blasting unit, one of said hoppers being opened to the interior of the housing in a region near the outer periphery of the same, and the other hopper being open to the interior of the housing in a region spaced inwardly from the outer periphery.

6. In a pipe cleaning machine, a housing adapted to generally surround and to be rotated about the pipe to be cleaned, means for rotating said housing about such pipe, said housing serving to contain a quantity of grits, a grit blasting unit carried by the housing and rotatable with the same, said unit including a rotary blasting wheel for centrifugal discharge of grits upon the pipe, and hopper means within the housing for supplying grits to a space provided within the blasting wheel, said wheel including means for storing a substantial quantity of grits within the same whereby the wheel provides a substantially

continuous blast of grits irrespective of temporary interruption in the supply of grits to said space.

7. In a pipe cleaning machine, a housing adapted to generally surround the pipe to be cleaned, said housing serving to contain a quantity of grits, a grit blasting unit carried by the housing, said unit including a rotary blasting wheel for centrifugal discharge of grits upon the pipe, and hopper means for supplying grits to a space provided within the wheel, said wheel including an inner set of distributing vanes surrounding said space, a set of circumferentially spaced plates surrounding the distributing vanes, and a set of impeller vanes surrounding said plates, said plates serving to provide for a storage of grits upon the inner faces of the same.

8. In a pipe cleaning machine, a housing adapted to generally surround the pipe to be cleaned, said housing serving to contain a quantity of grits, a grit blasting unit carried by the housing, said unit including a rotary blasting wheel for centrifugal discharge of grits upon the pipe, and hopper means for supplying grits to a space provided within the wheel, said wheel including an inner set of distributing vanes surrounding said space, a set of circumferentially spaced plates surrounding the distributing vanes and spaced radially from the same, a set of impeller vanes surrounding said plates and spaced radially from the latter, and a relatively stationary annular discharge control member interposed between the last named means and said plates, said member having an opening in the same for discharge of grits to the impeller vanes.

9. In a pipe cleaning machine, a housing adapted to generally surround the pipe to be cleaned, said housing serving to contain a quantity of grits, a grit blasting unit carried by the housing, said unit including a rotary blasting wheel for centrifugal discharge of grits upon the pipe, and hopper means for supplying grits to a space provided within the wheel, said hopper means including at least two hoppers and spouts leading from the same into said space, one of said hoppers being arranged to receive grits from a zone near the outer periphery of the housing, and the other hopper being arranged to receive grits from a zone nearer to the center of rotation of the housing.

10. In a machine of the character described, a grit blasting unit comprising a wheel adapted to be rotated, said wheel having an inner space adapted to receive grits, a set of annularly disposed vanes carried by the wheel and surrounding said space, said vanes serving to effect distribution of grits discharged through the same, a set of circumferentially spaced plates surrounding said vanes and spaced radially from the same, a set of impeller vanes carried by the wheel and surrounding said plates, and a relatively stationary annular discharge control member disposed between said plates and said impeller vanes, said member having an opening for discharge of grits to the impeller vanes.
